DECEASED, ASSIGNEES TO LACKAWANNA STEEL COMPANY, OF LACKAWANNA, NEW YORK, A CORPORATION OF NEW YORK.

SHEET-PILING WALL CONSTRUCTION.

1,422,821.

Specification of Letters Patent. Patented July 18, 1922.

Application filed July 7, 1915, Serial No. 38,609. Renewed November 26, 1919. Serial No. 340,800.

To all whom it may concern:

Be it known that we, CHARLES S. BOARDMAN and CLOUD CLIFFORD CONKLING, citizens of the United States, residing at Buffalo, in the county of Erie and State of New York, have invented new and useful Improvements in Sheet-Piling Wall Construction, of which the following is a specification.

10 This invention relates to walls composed of interlocking steel sheet piling and consists in an improved construction of wall and arrangement of the sheet-piling whereby there is produced a self-sustaining wall 15 of great strength having great resistance to upsetting stresses and not requiring anchor rods and anchors to assist the wall in sustaining the loads. In such a wall the amount of piling required for a given 20 strength of wall is reduced to a minimum and there is therefore a great reduction in cost. The characteristic of the wall is the zig-zag arrangement of a single series of piling producing a single wall composed of 25 sections set at an angle each to the two adjacent and connected sections. The wall may be suitably reinforced and braced to prevent movement or deformation of the piling-section and wall-elements, whereby 30 an integral and unitary wall is produced. The bracing or tie members may be arranged in various ways depending on the location, loads and requirements of the particular structure in question.

35 As is well known, interlocking sheet piling, commonly made of rolled steel, has of late become widely used in the construction of coffer-dams, bulk-heads, dock walls, dams and revetments. All of these are of 40 many different types and designs to adapt them to different conditions and locations. These various structures as heretofore built, may be divided into two main types—the single-wall, and the double-wall. The former in most cases is not self sustaining but 45 must be anchored or braced on the one side or the other.

In the latter type the two main walls, generally substantially parallel, are connected 50 by transverse division walls ties or struts dividing the space between the main walls more or less into pockets, commonly filled

with rock or earth to give weight and stability to the wall against overturning. Such double-wall or gravity wall structures have 55 wide bases and are self sustaining against upsetting stresses, due to the weight of the walls and the enclosed filling, together with the bending resistance of the sheet steel piles at or near their point of penetration in the 60 ground. Thus distinguishing from the single-wall or anchored construction the double wall construction requires a large amount of piling, substantially or usually three times that of the single wall type, not to 65 mention the large amount of interior filling, and therefore are expensive.

As distinguished from both these types of wall, we have invented the zig-zag or saw-tooth type, in which a continuous single wall 70 of piling is driven and arranged zig-zag so as to form a series of wall elements, each element arranged at an angle to each adjacent element, and thus affording a wide base and forming a self-sustaining wall, requiring much less piling, than the double type, therefore involving a great saving in expense with equal or greater strength. The angular arrangement provides corner 75 recesses for the filling at the back of the 80 wall as in permanent revetments, docks and bulk-heads.

Our invention further contemplates the bracing of the wall so formed to form a series of connected, self-contained wall elements or units, preferably of triangular form and further in the inter-relation of the units in a manner contributing greatly to the strength of the wall formed thereby and insuring against deformation of the individual units thereof.

In the drawings herewith are shown typical forms of wall illustrating our invention. Similar reference numerals are applied to similar parts in the various views. Fig. 1 85 is a horizontal cross section of our peculiar wall elaborately reinforced by compression and tension elements to resist the strains where a wall of great strength is required. Fig. 2 is a similar cross-section, showing 90 a smaller wall, and one reduced substantially to its simplest elements. Fig. 3 is a vertical cross-section of Fig. 1 showing the arrangement of filling in the recesses at the 95

rear of the wall. Fig. 4 shows enlarged the corner pieces of Fig. 1 for connecting the wall sections.

In the figures 1 indicates the individual sheet-piles driven vertically as nearly as may be, each pile interlocking with its neighbors, and arranged to form the reversely and angularly arranged sections of the single, continuous zig-zag wall. The 10 sections are connected by suitable corner pieces 2, of which a desirable fabricated form is shown in Fig. 4. A wide base wall is thus produced to resist overturning stresses without anchoring. The wall-sections as here shown, are set at an angle of 15 90° each to the other, which is desirable for most locations, but this angle may be greater or less depending on the height of the wall, the stresses to which it is exposed, and the 20 consequent width of base required.

Each section, by its angular arrangement, tends to brace the adjacent sections against direct stresses, more or less at a right angle to the particular section. But to prevent deformation and to produce a unitary structure adapted to resist various stresses, particularly those at right angles to the wall as a whole, it is important that the sections of the wall be braced by series of walling 25 timbers and compression members.

In Fig. 1 are shown two sets of continuous walling timbers the rear series 3 and the front 4, and from each corner of the wall there extends to the opposite walling timbers 30 the compression members or posts 6. These walling timbers are bolted or secured to the wall in any suitable manner for instance as shown in Figs. 1 and 4, set immediately outside of the exact corner to fill the space with- 35 in the flange on the T 11 of the corner pieces and there bolted. This T is a portion of the fabricated corner piece. It will be understood that usually there is one series of walling timbers on front and rear, conven- 40iently arranged at or near the surface of the water, but if required there may be one or more additional series, arranged below (or above) at such distance from the first series as the height of the wall and the stresses to 45 which it is subjected may make desirable.

As shown in Fig. 1, the compression members are in the form of timbers bolted to the other timbers, but in Fig. 2, in the form of bolts extending through holes in the corner 50 piles and in the walling timbers, so that they operate not merely as compression members but as bolts securing all the parts together.

Here in Fig. 2 the walling timbers are steel angles, whose vertical sides rest flat against 55 the corner piles and are punched for the bolts. And it will be understood that the mention of "timbers" does not limit us to the use of wooden beams or parts, but that steel structural shapes may be used where desir- 60 able.

Fig. 2 shows a simple form of our peculiar wall with the corners formed of a single pile bent along its longitudinal axis, and each angular section of the wall formed by a single straight pile and parts or halves of the corner pieces.

But in Fig. 1 a much more elaborate structure is illustrated with several piles in each section and additional bracing timbers and tie rods whereby is produced a wall having 75 a much wider base and adapted to resist great stresses. Here arched piling is used which gives greater strength and stiffness to each particular wall section. To receive the thrust and to support the interlocks of these 80 arched piles backing-timbers 8-8 are provided, which may be braced by braces 9-9, extending to the rear walling timbers 3, and by cross struts 10-10. These backing timbers may also be anchored by tie-rods 85 12-12, to the front walling timbers 4. Front and rear sets of tie-rods 13, 14 may be arranged preferably adjacent the walling timbers and extending through the T's more firmly to bind together the ends of the wall 90 sections.

As best seen in the simple form of Fig. 2, the use of walling timbers and compression members forms a wall, which at the point of application of said members and timbers is 95 a series of triangular trusses, the form best adapted to give the wall inherent strength and causes its units to act together in resisting the load.

As aforesaid, we have thus produced a 100 wall having the advantages of the double wall pocket type in being self-sustaining and resisting upsetting stresses by reason of its wide base, but obtaining this result with the use of much less sheet piling. Our wall with 105 the sections at 90° as suggested requires about 141% of the piling in a single straight wall whereas the pocket type requires about 300%. The expense of anchoring is saved by our walls which makes up largely for the 110 walling timbers, etc.

Furthermore in the pocket design the pockets are commonly filled with suitable material such as earth or rock to give weight to the structure and to prevent deformation 115 under load. In our wall the interior ties and struts take the place of this filling in preventing deformation and thus generally the expense and delay of filling is avoided.

In the preferred forms of our improved 120 wall, as here shown, it will be readily seen that by the use of the interior ties and struts between the angularly disposed walls at one side only thereof, there are thus formed a series of self contained triangular wall units 125 each of which is composed of the angularly positioned walls of piling with the backing members therefor when employed and the longitudinal walling timbers which form a skeleton base for the triangular unit so 130

formed. These units being of triangular truss form offer great resistance to deformation under all stresses and having a wide base give stability to the wall as a whole.

5 By providing the additional ties and struts on the opposite side of the wall it will be seen that additional and similar but reversely arranged horizontal trusses are formed. These additional trusses interact 10 with the truss forms of the opposite side of the wall in retaining the wall and the units from deformation and are also capable of independently acting upon the failure of the struts of one unit, thereby retaining proper 15 form of the piling wall and maintaining still a connected series of the triangular units. This feature of our invention thus provides for a wall composed of self contained units which may be of any desirable form and are 20 suitably connected to form interacting trusses whereby the units are connected to act together for strengthening and bracing the wall as a whole.

As indicated in the drawing when desired 25 the usual rip-rap or rock filling may be placed within the pockets of the wall to one side or the other as requirements demand for the purpose of giving added stability to the wall.

30 The particular structures here shown are intended as illustrations of many forms of wall in which our invention may be embodied and not in limiting sense. And it will be understood that any form of interlocking steel sheet piling may be used, and not merely the straight and arched forms with the peculiar interlocks here shown. Also it will be understood that the bracing of the wall may be accomplished in other 35 ways for instance when such wall is constructed to form a dock face the permanent dock structure may be constructed to act as a truss for supporting the wall of piling as will be readily understood.

40 Having described our invention we claim,—

1. A wall of sheet piling composed of triangular units, each formed of wall sections of interlocking sheet piling arranged in an

50 gular relation and sustaining members connected to the sections to form independently sustained units and to connect the units and therewith to form interacting trusses and the piling of said sections being interlocked in continuous saw tooth arrangement to form 55 a continuous wall and to connect the units substantially as described.

2. A wall of sheet piling, comprising interlocking sheet piles driven in saw-toothed or angular arrangement and interior ties and 60 struts arranged within the angular walls of piling to form independently connected triangular wall units adapted to produce a truss effect and each of said units being connected to the adjoining units by the continuous wall of interlocked piling.

3. A structure of the character described comprising a continuous single wall of interlocking sheet piling sections composed of 65 piling driven in saw-tooth or angular ar- 70 arrangement connected by corner or junction sections of similar piling elements having their webs angularly deformed and sustaining members connected to the respective corner piling sections to form independently 75 sustained and connected triangular units, substantially as described.

4. A structure of the character described comprising a continuous single wall of interlocking sheet piling sections composed of 80 piling driven in saw-tooth or angular ar- 85 arrangement connected by corner or junction sections of similar piling elements having their webs angularly deformed and sustaining members connected to the respective corner piling sections to form independently sustained and connected triangular units, said sustaining members comprising longitudinally extending structural steel beams positioned at the opposite sides of the piling 90 wall and connected by transversely arranged bolts passed through apertures in the corner piling sections, substantially as described.

In testimony whereof we have signed our names to this specification.

CHARLES S. BOARDMAN.
CLOUD CLIFFORD CONKLING.
